GAS TURBINE

Michael Martinka, Duisburg, Germany

Application February 6, 1937, Serial No. 124,407
In Germany July 1, 1936

13 Claims. (CL 60—41)

5 My invention relates to improvements in that class of rotary power producing machines, known as gas-combustion- or explosive-turbines, in which an elastic working fluid,—generally the gaseous combustion products of a mixture of fuel and air—violently flow at high velocity and temperature across the crown of blades of the rotary turbine wheel.

10 Turbines of that class, collectively hereinafter called "gas-turbines", are distinguished from the more widely known class of steam turbines by the unusually high range of temperatures,—ranging considerably above 500° centigrade,—at which the gaseous working medium reacts upon the blades 15 of the rotary turbine wheel, briefly hereinafter called "rotor", and by the greater working difficulties, generally accompanying high temperatures, and calling for extraordinary precautions—viz. the provision of highly efficient cooling expedients—in order to prevent destructive overstraining of the material, of which the rotor, its web and its blades are made.

20 As a matter of fact, the rotary speed, at which gas-turbines can be safely worked, and on which their efficiency largely depends, is limited

25 1. Because of the heat radially flowing from the highly heated blades into the rim of the rotor, wherein the blades are fixed,—namely by what may be conveniently called the "heat" stresses induced in said rim by the great drop of temperatures, from t to t_2 , which are diagrammatically indicated in Fig. 12, and

30 2. Because of the mechanical stresses, which are imparted in addition to the heat stresses to the rotor rim, by the violent centrifugal forces 35 produced, while the turbine is in operation.

35 Practical experiments made with gas-turbines in state of development have shown, that the rotor rim is one of their most critical and perilous parts, and that the maximum rotary speed, at which the rotor can be safely revolved under the existing conditions, and with the cooling expedients known is about 230 meters per second measured at the blades:

40 45 Briefly stated the invention aims at providing a structurally improved gas-turbine, which can be safely worked at a higher speed, and which will show a higher efficiency, and a greater output in horsepower units per unit of weight of the turbine,—the ultimate object being to make the 50 improved gas-turbine fit for being used even on aeroplanes, Zeppelin-air-ships, and kindred air craft, where the light weight of the motors and safety of their operation are the predominant 55 considerations.

In connection with the above described principal object, the invention aims at practically intercepting the flow of heat from the blades into the rotor rim proper and its web, by so designing the turbine rotor and its blades, and so associating them with structurally simple, reliable cooling expedients, gently acting by means of gases, that the temperatures throughout the web are practically equal and uniform.

5 The invention employs gaseous currents for 10 cooling the roots of the blades hereinafter called "shanks"; the latter are preferably elongated in radial direction, and are provided with recesses enclosing cooling chambers, and with anchors for fixing those blade structures in the rim of the 15 turbine wheel.

Another salient feature of the invention is the 20 provision of means for cooling the web of the turbine wheel by means of currents of a gaseous agent, recirculated in closed cycles of movement 25 therearound, and of means for re-cooling the said gaseous currents in a specific graduated manner, namely in proportion to the respective amounts of heat to be dissipated at the said shanks of the blades and at the various zones of the web of the 25 turbine wheel,—and with the object of keeping the temperatures relatively low and practically constant and uniform throughout the whole web.

The nature and scope of the invention are 30 briefly outlined in the appended claims, and will 35 be more fully understood from the following specification taken together with the accompanying drawings, in which a gas-turbine redesigned according to this invention is shown by way of an example:

35 Fig. 1 is a fragmentary section taken vertically through the turbine on line I—I in Fig. 2;

Fig. 2 is a side elevation of the turbine, drawn on a smaller scale;

40 Figs. 3 and 4 show in enlarged scale the annular cooling ribs, enclosing the web of the turbine wheel, in cross section and in side elevation;

45 Figs. 5 and 6 show perspective the blades redesigned according to this invention;

Figs. 7 and 8 are side elevations showing one of 45 the blades with their shank as seen from either side;

50 Fig. 9 is a cross section taken at right angles to the axis of the turbine wheel through the blades;

Fig. 10 is a cross section taken through the blades and their shanks on line X—X in Fig. 9;

55 Fig. 11 shows the turbine wheel alone in cross section with reference to

Fig. 12, which is a diagram, shows the de- 55

velopment of temperatures within the blades, their shanks, the rim, web and nave of the turbine wheel.

With the objects in view outlined above the 5 gas-turbine re-designed according to this invention essentially consists of:

1. A housing or "stator" 20, 21, formed with a combustion chamber 22 of substantially circular cross sectional shape having a cooling jacket 22' 10 and being connected with pipes, not shown, through which fuel and air are supplied thereinto; the gaseous products of combustion pass through an intake nozzle 23 on their way to the blades of the turbine wheel described herein- 15 after, and finally escape through the discharge nozzle 24,

2. Ribbed radiators presenting annular recesses, in which a gaseous cooling medium circulates, the latter being re-cooled by

20 3. Cooling jackets, through which cooling liquids, preferably water, circulate:

The said radiators comprise two pairs of cooling ribs 30, 30', 32, 32', enclosing annular recesses r , r' (Fig. 3) of approximately circular cross sectional shape, and another pair of cooling ribs 34, 34', which jointly enclose an annular recess of substantially oval cross sectional shape r'' and closely surround at both sides the respective cooling elements attached to and integrated with the blades 3a, 3b of the turbine wheel referred to in detail hereinafter.

The radiator ribs 32, 32' and 34, 34' are in direct contact with the cooling medium passing through the cooling jackets 42, 42' and 44, 44', 35 while the ribs 30, 30' and jackets 40, 40' are spaced from each other, so as to indirectly act upon each other through radiation.

The stator 20, 21 of the gas-turbine encloses the bladed turbine wheel or rotor, journaled 40 therein at 25, 26 and comprising

4. A web 50, which is preferably integral with the nave 52 of the rotor;

5. Toothed prongs 55, radially projecting from said web 40, the lateral faces or flanks of said 45 prongs extending parallel to the axis of the turbine wheel;

6. A crown of blades attached to the rim of the rotor, and consisting of pairs of differently shaped blade structures, the blades proper of which 3a, 3b are attached to shanks 4a, 4b, and are secured to the rotor rim by means of toothed roots or anchors 5a, 5b, projecting from said shanks; the flanks of said anchors are axially directed, so as to engage the corresponding faces of said prongs 55 of the turbine wheel.

The said shanks 4a, 4b, provided and arranged according to this invention and in contradistinction to prior art gas-turbines intermediate the blades and their roots, are so designed as to 60 act at the same time as blade carriers, and blade cooling and spacing members, namely to keep the blades 3a, 3b—being the hottest portion of those blade structures—a considerable distance apart from the rotor rim, its prongs 55, and the 65 rotor web,—thus providing a zone of ample width, which is not integral with the rotor rim, but only in contact therewith, and wherein the drastic drop of temperatures from t to t_2 referred to above and shown in Fig. 12 takes place.

70 A salient feature of said blade structures, not visible in the drawings, consists therein, that they are fitted together and into their places at the rotor rim with such allowances as to their width, that they are capable of individually expanding to a predetermined extent, so chosen

as to prevent excessive "heat" stresses of the character described in the preamble, which would occur, if the blade structures were fitted rather tightly and under considerable initial pressure against each other, and into their 5 places between the prongs 55 of the turbine wheel.

For cooling purposes the said shanks 4a, 4b are preferably of double T or I cross sectional shape, best seen in Fig. 10 at the right, namely 10 they are formed with lateral walls having holes 4c, 4c', 4d, 4d', and recesses 4e, 4e', so designed, that every two blade structures adjacently disposed to each other present a cooling chamber having an intake port at 4e, 4e', and two discharge holes 4c, 4c'.

The anchors 5a, 5b of the blade shanks terminate short of the root portions of the prongs 55, so as to enclose intake ports 55', and are formed with a plurality of grooves opposed to each other, 20 presenting channels 5i, through which the cooling air, drawn in through intake ports 55', passes into the respective cooling chambers; the courses taken by the currents of cooling gas passing through the cooling chambers enclosed between 25 every two adjacently disposed blade structures are indicated in Figs. 6-8 by lead lines and arrows x , y .

The blades 3a, 3b are provided with holes 3c and rectangular flanges 3e projecting from their 30 upper faces, so as to present at their outer ends a practically non-interrupted cylindrical surface except for the said holes; the same is true with regard to the lower and inner ends of the blades 3a, 3b, where corresponding flanges 3f' are provided, fitting together so as to present a continuous line of border elements; as seen on Figs. 5, 6, 10 said lower flanges are formed at their bottom with curved faces 3o for deflecting the cooling air, discharged through the holes 4c, 4c', 40 4d, 4d'.

The operation of the cooling expedients provided at the gas-turbine described above is as follows:

The bulk of the heat passing by conduction 45 from the highly heated crown of blades into their shanks 4a, 4b is transferred therefrom to the currents of cooling gas, which are positively circulated through the respective cooling chambers, shown and described with reference to 50 arrows x and y by centrifugal forces, produced and comparable to those active in a bladed centrifugal fan or pump. The drop of temperatures, provoked within the shanks 4a, 4b of the blade structures, is indicated by diagram line 55 $t-t_2$ in Fig. 12.

The heated gas discharged through the holes 4c, 4c', 4d, 4d' is intensely re-cooled on travelling across the opposed cooling ribs 34, 34', the rear faces of which are in direct contact with the 60 liquid cooling medium passing through the jackets 42, 42' and 44, 44'.

Likewise another proportion of the heat, which by conduction reaches the anchors 5a, 5b of the blade structures and the prongs 55 of the rotor 65 rim is transferred therefrom and dissipated by those currents of cooling gas indicated at y in Figs. 6 and 7, namely passing through the intake ports 55' and through the channels 5i; the change of temperatures being indicated in Fig. 12 70 by diagram line t_2-t_3 .

The rest of the heat reaching on its travel in radial direction the web proper of the turbine wheel is transferred therefrom by all those annular currents of cooling gas, which are enclosed 75

by the ribs 30, 30', 32, 32', and are forced to travel therebetween in circumferential direction indicated by arrow 2 (Fig. 4) by reason of their frictional contact with the surfaces of the web

5 40.

The said cooling ribs 30, 30', 32, 32', and in turn the currents of gas circulating therebetween are recooled, substantially in proportion to the decreasing amounts of heat to be dissipated by 10 the cooling jackets 42, 42', which are in direct contact with the ribs 32, 32',—and by the cooling jackets 40, 40' arranged at a distance from the ribs 30, 30', so as to indirectly act upon each other through radiation.

15 Various changes and modifications may be conveniently made in the structural details of gas-turbines of the improved design described and in the shape, assemblage and cooperation of their cooling expedients, without departing from the 20 spirit and the salient ideas of this invention:

For instance guide elements in the form of twisted strips of sheet steel, of which a short piece is shown at 60 in Fig. 4, may be provided within the recesses enclosed by the ribs 30, 30', 25 32, 32', in order to cause the annular currents of cooling gas, travelling in circumferential direction, to attain at the same time a twisting motion, and to thereby enhance the efficiency of both the primary and secondary cooling medium.

30 The secondary cooling medium—preferably water—should be positively circulated by a pump P (Fig. 2) through the cooling jackets in the direction of the arrows $i-o$ and $i'-o'$, and be re-cooled by a radiator R or other appropriate means 35 known per se and shown in Fig. 2:

In other words the coolest water should enter the jackets 44, 44' opposed to the shanks 4a, 4b of the turbine blades, in order to most effectively cool the hottest part of the rotor; and should 40 thence pass through the jackets 42—40, and 42'—40', in such manner, that the cooling effect is graduated according to local heat conditions at the rotor rim and web.

What I claim is:

45 1. In a gas-turbine, having a bladed rotor and a housing, enclosing and supporting said rotor, the combination with a crown of blade structures, having anchors for fixing the blades at the rotor rim and relatively wide, hollow shanks arranged 50 intermediate the said anchors and the blades proper,—of primary cooling means, employing a plurality of gaseous currents re-circulated in closed cycles of movement through said hollow shanks and around the rim and web of the 55 rotor,—and secondary cooling means for re-cooling the respective gaseous currents in proportion to the amount of heat to be locally dissipated.

2. In a gas-turbine, having a bladed rotor and a housing, enclosing and supporting said rotor, 60 the combination with a crown of blade structures, having anchors for fixing the blades at the rotor rim and relatively wide, hollow shanks arranged intermediate the said anchors and the blades proper,—of primary cooling means, employing a 65 plurality of gaseous currents re-circulated in closed cycles of movement through said hollow shanks and around the rim and web of the rotor,—and secondary cooling means for re-cooling the respective gaseous currents in proportion 70 to the amount of heat to be locally dissipated,—said shanks being of I cross sectional shape so as to present recesses at opposed sides so interengaging each other, that every two adjacently disposed blade structures enclose a cooling chamber.

75 3. In a gas-turbine, having a bladed rotor and

a housing, enclosing and supporting said rotor, the combination with a crown of blade structures, having anchors for fixing the blades at the rotor rim and relatively wide, hollow shanks arranged intermediate the said anchors and the blades proper,—of primary cooling means, employing a plurality of gaseous currents re-circulated in closed cycles of movement through said hollow shanks and around the rim and web of the rotor,—and secondary cooling means for re-cooling the respective gaseous currents in proportion to the amount of heat to be locally dissipated, said shanks being of I cross sectional shape so as to present recesses at opposed sides so interengaging each other, that every two adjacently disposed 15 blade structures enclose a cooling chamber,—the latter being provided with intake ports and discharge holes at their lower and upper ends.

4. In a gas-turbine, having a bladed rotor and a housing, enclosing and supporting said rotor, the combination with a crown of blade structures, having anchors for fixing the blades at the rotor rim and relatively wide, hollow shanks arranged intermediate the said anchors and the blades proper,—of primary cooling means, employing a plurality of gaseous currents re-circulated in closed cycles of movement through said hollow shanks and around the rim and web of the rotor,—and secondary cooling means for re-cooling the respective gaseous currents in proportion to the amount of heat to be locally dissipated,—the rotor rim presenting toothed prongs, spaced from each other for engagement with pairs of said anchors of the blades.

5. In a gas-turbine, having a bladed rotor and a housing, enclosing and supporting said rotor, the combination with a crown of blade structures, having anchors for fixing the blades at the rotor rim and relatively wide, hollow shanks arranged intermediate the said anchors and the blades proper,—of primary cooling means, employing a plurality of gaseous currents re-circulated in closed cycles of movement through said hollow shanks and around the rim and web of the rotor,—and secondary cooling means for re-cooling the respective gaseous currents in proportion to the amount of heat to be locally dissipated,—the said anchors of the blades being formed with radial channels and presenting intake ports for the gaseous currents at the rim 50 of the rotor.

6. In a gas-turbine, having a bladed rotor and a housing, enclosing and supporting said rotor, the combination with a crown of blade structures, having anchors for fixing the blades at the 55 rotor rim and relatively wide, hollow shanks arranged intermediate the said anchors and the blades proper,—of primary cooling means, employing a plurality of gaseous currents re-circulated in closed cycles of movement through said hollow shanks and around the rim and web of the rotor,—and secondary cooling means for re-cooling the respective gaseous currents in proportion to the amount of heat to be locally dissipated,—the rotor being formed with spaced 60 prongs for engagement with the anchors of the turbine blades, the latter being proportioned and mounted in their places with such allowances in cold condition, that they are capable of individually expanding in heated condition.

7. In a gas-turbine, having a bladed rotor and a housing, enclosing and supporting said rotor, the combination with a crown of blade structures, having anchors for fixing the blades at the 65 rotor rim and relatively wide, hollow shanks ar-

70

75

- ranged intermediate the said anchors and the blades proper,—of primary cooling means, employing a plurality of gaseous currents re-circulated in closed cycles of movement through said hollow shanks and around the rim and web of the rotor,—and secondary cooling means for re-cooling the respective gaseous currents in proportion to the amount of heat to be locally dissipated,—the said primary cooling means comprising a plurality of cooling ribs, the front faces of which being opposed to said shanks and anchors of the blade structures, and to the rim and web of the rotor respectively, while their rear faces are opposed to the said secondary cooling means.
8. In a gas-turbine, having a bladed rotor and a housing, enclosing and supporting said rotor, the combination with a crown of blade structures, having anchors for fixing the blades at the rotor rim and relatively wide, hollow shanks arranged intermediate the said anchors and the blades proper,—of primary cooling means, employing a plurality of gaseous currents re-circulated in closed cycles of movement through said hollow shanks and around the rim and web of the rotor,—and secondary cooling means for re-cooling the respective gaseous currents in proportion to the amount of heat to be locally dissipated, the said primary cooling means comprising a plurality of cooling ribs, the front faces of which being opposed to said shanks and anchors of the blade structures, and to the rim and web of the rotor respectively, while their rear faces are opposed to the said secondary cooling means,—the latter employing a liquid cooling agent.
9. In a gas-turbine, having a bladed rotor and a housing, enclosing and supporting said rotor, the combination with a crown of blade structures, having anchors for fixing the blades at the rotor rim and relatively wide, hollow shanks arranged intermediate the said anchors and the blades proper,—if primary cooling means, employing a plurality of gaseous currents re-circulated in closed cycles of movement through said hollow shanks and around the rim and web of the rotor,—and secondary cooling means for re-cooling the respective gaseous currents in proportion to the amount of heat to be locally dissipated, the said primary cooling means comprising a plurality of cooling ribs, the front faces of which being opposed to said shanks and anchors of the blade structures, and to the rim and web of the rotor respectively, while their rear faces are opposed to the said secondary cooling means, the latter employing a liquid cooling agent,—and comprising a plurality of ring shaped jackets, through which said liquid cooling agent circulates.
10. In a gas-turbine, having a bladed rotor and a housing, enclosing and supporting said rotor, the combination with a crown of blade structures, having anchors for fixing the blades at the rotor rim and relatively wide, hollow shanks arranged intermediate the said anchors and the blades proper,—of primary cooling means, employing a plurality of gaseous currents re-circulated in closed cycles of movement through said hollow shanks and around the rim and web of the rotor,—and secondary cooling means for re-cooling the respective gaseous currents in proportion to the amount of heat to be locally dissipated, the said primary cooling means comprising a plurality of cooling ribs, the front faces of which being opposed to said shanks and anchors of the blade structures, and to the rim and web of the rotor respectively, while their rear faces are opposed to the said secondary cooling means, the latter employing a liquid cooling agent, and comprising a plurality of ring shaped jackets, through which said liquid cooling agent circulates,—and which are interconnected in series so that the coolest liquid enters the outermost cooling jackets.
11. In a gas-turbine, having a bladed rotor and a housing, enclosing and supporting said rotor, the combination with a crown of blade structures, having anchors for fixing the blades at the rotor rim and relatively wide, hollow shanks arranged intermediate the said anchors and the blades proper,—of primary cooling means, employing a plurality of gaseous currents re-circulated in closed cycles of movement through said hollow shanks and around the rim and web of the rotor,—and secondary cooling means for re-cooling the respective gaseous currents in proportion to the amount of heat to be locally dissipated, the said primary cooling means comprising a plurality of cooling ribs, the front faces of which being opposed to said shanks and anchors of the blade structures, and to the rim and web of the rotor respectively, while their rear faces are opposed to the said secondary cooling means,—the cooling ribs, opposed to the rotor rim and web enclosing annular spaces, wherein twisted strips are provided adapted to act as guide elements and causing the gaseous currents circulating therebetween to perform at the same time a trundling motion.
12. In a gas-turbine, having a bladed rotor and a housing, enclosing and supporting said rotor, the combination with a crown of blade structures, having anchors for fixing the blades at the rotor rim and relatively wide, hollow shanks arranged intermediate the said anchors and the blades proper,—of primary cooling means, employing a plurality of gaseous currents re-circulated in closed cycles of movement through said hollow shanks and around the rim and web of the rotor,—and secondary cooling means for re-cooling the respective gaseous currents in proportion to the amount of heat to be locally dissipated, the said primary cooling means comprising a plurality of cooling ribs, the front faces of which being opposed to said shanks and anchors of the blade structures, and to the rim and web of the rotor respectively, while their rear faces are opposed to the said secondary cooling means, the latter employing a liquid cooling agent, and comprising a plurality of ring shaped jackets, through which said liquid cooling agent circulates,—and which are interconnected in series so that the coolest liquid enters the outermost cooling jackets.

MICHAEL MARTINKA.
